(57) **CLAIM**

The ornamental design for a display screen with an animated graphical user interface, as shown and described herein.

DESCRIPTION

FIG. 1 is a front view of a display screen with an animated graphical user interface showing a first image in a sequence; FIG. 2 is a second image thereof; FIG. 3 is a third image thereof; FIG. 4 is a fourth image thereof; and, FIG. 5 is a fifth image thereof.

The innermost rounded rectangle broken line shows the display screen. All broken lines outside the display screen show an electronic device. All broken lines within the display screen show portions of the graphical user interface. The broken lines form no part of the claimed design. The appearance of the animated graphical user interface sequentially transitions between the images shown in FIGS. 1-5. The process or period in which one image transitions to another image forms no part of the claimed design.
